UNITED STATES PATENT OFFICE

ANNIE DAVIS, OF SCRANTON, PENNSYLVANIA.

STAIR-ROD.

No. 900,358

Specification of Letters Patent.

Patented Oct. 6, 1908.

Application filed March 27, 1908. Serial No. 423,596.

To all whom it may concern:

Be it known that I, ANNIE DAVIS, a citizen of the United States, residing at Scranton, in the county of Lackawanna, State of Pennsylvania, have invented certain new and useful Improvements in Stair-Rods; and I do hereby declare the following to be a full, clear, and exact description of the invention, such as will enable others skilled in the art to 10 which it appertains to make and use the same.

This invention relates to certain new and useful improvements in stair rods.

The object of my invention is, to provide a 15 stair rod so constructed, that the same may be adjustably secured to the riser of a stair, and while in its adjusted position may be shifted to stretch the carpet, the rod being easily fixed after the proper adjustment has 20 been secured, and my invention embodies certain other features of construction, as will be more fully described hereinafter.

In the accompanying drawings, I have shown in Figure 1 is an elevation of my 25 proved stair rod and fastener securing a strip of carpet. Fig. 2 shows a detached front view of a stair rod embodying my invention. Fig. 3 is a rear view, and Fig. 4, a central sectional view.

30 The purpose of this invention is to provide a neat and simply constructed stair rod arranged not only to securely hold the stair carpet to the stair, but so that the stair rod may be used in stretching the carpet during 35 the operation of securing the stair rod.

In the accompanying drawings 5 indicates a stair rod of any suitable length which is recessed, and provided at each end with the securing base portions, 6, 6 so that by means 40 of these projecting base portions, I provide a stair rod having the raised under portion or surface 7, as disclosed in Fig. 4. At each end, the securing base portions 6 are recessed so as to snugly receive the plates 10, 10, these 45 plates forming securing ears, each being provided with a key-hole slot embodying the eye 11 and slot 12, as disclosed.

Held within the recesses 13 positioned at suitable points intermediate of the ends of 50 the rod are the carpet securing teeth 15, these teeth being provided with the offset portions 16, and perforated base portions 17, and are secured by means of the screws 19, as indicated in Fig. 3.

55 In referring to the drawings, it will be noticed that the securing ears 10 are projected

parallel and in like directions. These laterally extending ears may be suitably embellished, as may also the rod 5.

In Fig. 1, *a* represents the tread and *b* the 60 riser of a stair to which the carpet A is secured by means of one of my improved stair rods.

In the operation of securing a stair carpet by means of these stair rods, the stair carpet 65 is first placed upon the stairs when a plurality of round headed screws are secured within the riser at the sides of the carpet at predetermined points, as shown for instance in Fig. 1. The upper end of the stair carpet is then secured. The first rod is then secured to its screws 20 in passing the heads of the screws through the eyes 11 and then carrying the stair rod 5 downward so that the neck of the screws will be held within the 70 slots of the securing ears. The stair carpet is then drawn taut when the stair rod is forced downward, so that the teeth points 15 which project slightly beyond the lower edge of the stair rod will engage the carpet and as 75 the rod is forced down into its lowermost position, the carpet is carried with the rod. When the final adjustment has been secured, the screws are driven home to securely fasten the ears and thereby the connected rod. As 80 the points 15 project below the lower edge of the stair rods they may also be driven a short distance into the tread of the stair to prevent any displacement of the stair rod when the carpet is pulled in stretching, the 85 same.

My construction method insures a neat and simply constructed stair rod which can be readily applied as well as removed.

And having thus described my said invention, what I claim as new and desire to secure by U. S. Letters Patent is—

1. The combination with a stair rod having a securing base at each end, the bottom of said stair rod being recessed between said 95 base ends, an ear secured to each of said bases, teeth projecting beyond one edge of said rod and means to secure said ears.

2. The combination with a stair rod having a projecting securing base at each end, of 100 a securing ear extending from each of said base ends, said ears being projected parallel and in like direction, means to adjustably secure said ears, and teeth secured to said rod intermediate of said base ends.

3. The combination with a recessed stair rod, of a laterally extending securing ear

fixed to the base of said rod at each end, each of said ears extending in like direction and having a key-hole slot and a plurality of offset teeth secured to the under surface of said 5 bar, said teeth extending beyond the edge of said bar all arranged as and for the purpose set forth.

In testimony whereof, I affix my signature, in presence of two witnesses.

ANNIE DAVIS.
